UNITED STATES PATENT OFFICE.

JOSEPH H. DICKINSON, OF CRANFORD, NEW JERSEY, ASSIGNOR TO THE AEOLIAN COMPANY, A CORPORATION OF CONNECTICUT.

TALKING-MACHINE.

1,279,522.

Specification of Letters Patent. Patented Sept. 24, 1918.

Application filed March 31, 1914. Serial No. 828,445.

To all whom it may concern:

Be it known that I, JOSEPH H. DICKINSON, a citizen of the United States, residing at Cranford, Union county, New Jersey, have invented a new and useful Improvement in Talking-Machines, of which the following is a specification.

My present invention relates to the hereinafter shown or described improvements in talking machines, phonographs and the like.

In the drawings, which show only some of the specific embodiments that my improvements are adapted to take, Figure 1 is a front view of the instrument having the front wall of the casing removed to show the contained parts, and showing the lid elevated with its upper portion broken away; Fig. 2 is a longitudinal sectional view, on a relatively enlarged scale, of the handle and flexible control devices for operating the dynamics control valve and the brake; Fig. 3 is a top plan view of the instrument with the lid raised and with a portion of the permanent top 31 of the right hand portion 15 of the instrument broken away to reveal the underneath structure; Fig. 4 is an enlarged detail showing how the small neck end of the horn is supported in insulated manner on the bottom board of the instrument; Fig. 5 is an underneath plan view of the instrument; Fig. 6 is an enlarged sectional view on the line 6—6 in Fig. 5 looking in the direction of the arrows; Fig. 7 is an enlargement of the middle portion of Fig. 1; Fig. 8 is an enlarged detail of the brake means looked at from the front of the instrument; Fig. 9 is an enlarged detail of the dial pointer means for setting the dynamics control valve so that the instrument 20 will play with a degree of loudness indicated by the pointer, the view being a sectional view on the line 9—9 Fig. 3 looking in the direction of the arrows; Fig. 10 is an enlarged detail showing a modification of the means provided for making a sound-tight joint between the lid and the body of the casing of the instrument; Fig. 11 is a view of the horn and casing of the instrument looked at from the right hand end of Fig. 12; Fig. 12 is a longitudinal section through the same parts shown in Fig. 11; Fig. 13 is a top plan view of the same parts showing horn broken away to reveal the underlying structure.

55 I will now describe the specific devices

of the drawings, reserving it to the claims to point out the novel features and to define the scope of the invention, it being understood that the claims will be given the due range of equivalents to which they may be entitled in view of the art.

The instrument has a segmental shaped casing and is like a consol table supported on legs, but this particular form is, of course, immaterial. The left hand end of the casing is reserved for the motor 1, turntable 2, reproducer 3, and tone arm 4, and the right hand end for the horn 5. 6 is a horizontal shelf supported intermediate the top and bottom of the casing. Below it is the motor 7 and through it vertically extends the spindle 7 of said motor, on whose upper end above the shelf is the usual turntable 2 to support the record disk 8. In Fig. 1, the reproducer 3 is shown with its stylus in operative engagement with the record.

The horn may have the rectangular cross section shown in Fig. 11, and be made of suitable sheet metal and may have the round sectioned small end or neck 9 which curves upwardly through a relatively much larger hole 10 in the shelf 6, so that there is an air clearance all around it without its touching the shelf. The horn is secured to the bottom board of the casing by means as follows: Its neck 9 has a flat-bottomed boss 12 formed on its under side (compare Fig. 4). 13 is a transversely extending plate screwed to said boss. This plate in turn is secured by screws 15 to the bottom of the casing with a strip of felt or other sound-deadening material 14 under it and washers 16 of similar material above it, and further there may be similar bushings 17 provided to surround the screws.

95 The neck 18 of the reproducer (Fig. 1) telescopes with the free end of the tone arm 4, permitting the former to be rotated about the longitudinal axis of said neck into and out of operating position. The curved tone 100 arm has an even bore and swivels horizontally, being supported on a tubular cap 19 on the above described upturned neck of the horn (compare Figs. 1 and 7). 20 is an upright from this cap having a hearing 105 for the swivel pin 21 that projects axially upward from the tone arm.

22 is a rubber throat having a circular flange 23 and a tubular portion 24 tapering in thickness to its mouth. 25 is a plug 110

valve coöperating with the bore of this throat and is mounted on the vertically reciprocatory stem 26, which latter is guided above in a hole in a cross piece 27 and extends below through a hole 28 in the lower wall of the neck of the horn.

The throat and valve form a tone and dynamics regulating means, elsewhere patented. The throat is held in position by 10 screws 29 which clamp its flange between the cap 19 and the top of the neck 9.

It will be noted that the horn is substantially insulated from the casing by the described supporting means shown in detail 15 in Fig. 4, as are also the tone arm and the reproducer, because these are supported on said insulated horn.

30 (Figs. 1, 3 and 7) is a vertical partition extending upwardly from the shelf 6, 20 and 31 is a permanent cover over the horn part of the casing flush with its upper edge. The lid 32 hinged at its straight edge is co-extensive with the top of the entire instrument, and when raised uncovers the left 25 hand part of the instrument, thereby giving access to the reproducer and the turntable to adjust and change records.

33 is a folded or doubled over strip of felt or equivalent packing material for the purpose, secured by cleat 34 and screws 35 in 30 the form of an edging around the mouth of this left hand part of the casing (compare Figs. 3 and 7). This felt, as shown in the latter figure, projects above the actual rim 35 of the opening so as to contact snugly with the lid 32 when closed, and thereby prevent mechanical noise, due to the operation of the instrument, from escaping into the room.

Fig. 10 shows a modification of this feature, wherein the felt material 36 is mounted to project from a groove in the lid and contacts with a correspondingly placed rigid strip or bead 37 on the other part of the casing of the instrument.

45 Further, to complete the description of the externals of the instrument, 38 is a curved door (Fig. 3) hinged at 39 which, when closed, continues and completes the curved front of the instrument. 40 is a 50 curved, vertically positioned, stationary piece of board leading from the rear edge of the horn to the rear edge of the door. The legs of the instrument are designated 41.

42 is the usual motor winding-handle inserable through a hole in the front of the instrument into engagement with the winding stem 43 of the spring motor 1, which latter may be of any usual or preferred construction.

60 Means are provided so that the operator can continuously operate the throat valve 25 to vary the dynamics and the quality of the tones in sympathetic accord with the record being played; or the operator may move a 65 pointer over a dial, marked from double

piano to double forte, to any desired indication which will automatically adjust the aforesaid valve to a corresponding position relative to the throat, so that the instrument thereafter will play with the degree of dynamics indicated on the dial until the pointer is adjusted to a new position, or until the first named means is operated. The combination of means by which these two instrumentalities both act on the same valve without interference with each other will now be described.

The valve stem 26, as shown in Fig. 1 and in the enlarged view Fig. 6, projects through a hole in the bottom of the instrument where it connects by a link 44 and by a crank arm 45 (compare the underneath plan view Fig. 5) on a stub-shaft 46 journaled in two wooden blocks 47 secured to the bottom board 11 of the instrument. The actual 85 bearings consist of pieces of felt 48 wrapped around the stub-shaft and themselves located in squared holes in the blocks. 49 is a further crank arm on the stub-shaft whose free end connects by a tension spring 50 90 with the casing of the instrument. The net result is that the valve stem 26 and the valve are normally spring-held in their lowermost position away from the throat, which is accordingly normally wide open for loudest 95 playing.

51 and 52 are a pair of similar wood arms mounted on either side of the aforesaid crank arm 49 but, unlike it, they each swing loosely and independently on the shaft 46. 100 A connecting rod 53 runs from the free end of the arm 51 and a rod 54 from the arm 52. 55 is a pin extending through the crank arm 49 with its respective ends located in the path of these swinging arms 51 and 52, 105 which latter, where they contact with the pin, are faced with felt as best shown at *a* in Fig. 6, the object being to secure noiseless operation. The net result of the foregoing devices is that when the connecting 110 rod 53 is pulled by intermediate means connected with the pointer 56 adjustable over the dynamics dial 57, it swings its connected arm 51 into contact with the aforesaid pin 55 and thereupon carries the crank arm 49 115 with it against the tension of the spring 50, and so adjusts the throat valve toward and perhaps into the throat to an extent corresponding in playing effect to the indicated adjustment of the pointer on the dial. The 120 intermediate connections between said pointer 56 and said connecting rod 53 are as follows: In the first place, the pointer is placed horizontally over the dial 57 (see top plan view of the instrument Fig. 3), 125 and the dial is set down into an opening (Fig. 9) in the permanent cover 31 of the horn side of the instrument. The pointer is secured to the suitably journaled vertical stub-shaft 58 (Fig. 9) which at the bottom 130

of the instrument is provided with a crank arm 59, the latter connecting with the rod 53, thereby completing the operative connection between the dial-pointer, the swinging arm 51 and therefore the valve stem 26.

Like the arm 51, the other swinging arm 52 when pulled by its rod 54 strikes the pin 55 and carries the crank arm 49 to operate the throat valve toward its closed position; but the difference is that said rod 54 connects with an adjusting means which, in the hands of the operator, is adapted to be continuously delicately adjusted to vary the tonal effects sympathetically with the composition being played.

This means comprises a handle 60 shown in the enlarged view Fig. 2, and having a long flexible control 61 running to the instrument. More in detail, said handle consists of an outer tubular part 62 and an inner reciprocating stem 63 having an enlarged head 64. The wire control comprises a wire 65 slideable in a surrounding flexible casing 66, the latter in turn consisting of a closely coiled wire having fabric woven about it. As shown in Fig. 2, the tubular part 62 of the handle is attached to the casing 66 of the flexible control, and the inner handle part 63 is attached to the wire 65.

At the other end, said casing 66 is attached to a tubular part 67 secured to the bottom board 11 of the instrument, whereas the wire 65 is attached to a slide rod 68 working in a suitable bore through the part 67 (Fig. 2). This slide rod connects by link 69 with one arm of a bell crank lever 70 whose other arm connects with the connecting rod 54 previously described. This completes the description of the operating connections between the handle 60 and the swinging arm 52, and therefore the throat valve stem 26, whence it will be seen that when the operator pulls the head 64 of the handle (Fig. 2) out of its tubular part 62, he, to that extent, proportionately adjusts the throat valve toward its closed position against the tension of the spring 50, which vice versa tends to open the valve whenever the pull on the head of the handle is relaxed.

This handle 60, when not in use, is conveniently supportable in the open-ended cleat 71 on the underside of the instrument (Fig. 5). 72 is a similar cleat except that it is open at both ends to support the flexible control whose length is such, it will be noted, that the instrument can be operated and its tonal effects delicately varied from a considerable distance in any direction away from the instrument.

A feature of the aforesaid flexible control is the provision of further means in combination therewith for throwing on the brake to stop the turntable after the record has been played, thereby avoiding any necessity for rushing to the instrument for

this purpose. An extra sleeve 73 (Fig. 2) is provided in the handle having a knob 73^a projecting through a longitudinal slot in the outer sleeve 62. This inner sleeve connects with an extra wire 74 in the flexible 70 casing 66 which wire at its other end connects with a slide rod 75. A link 76 connects the latter with the centrally fulcrumed lever 77. This lever in turn is connected by a rod 78 with crank arm 79 on a suitably journaled vertical stub-shaft 80 (compare Fig. 8), whose upper end has a further crank arm 81 (compare Fig. 3) adapted when the shaft is rotated by a pull on the aforesaid wire 74 of the flexible control by the knob 73^a, to 80 contact with the brake handle 83 (Figs. 3 and 8) to push its friction member against the periphery of the turntable to stop its rotation until again released.

In addition, this brake can be directly 85 operated from its handle 83 when the lid 32 is raised or when it is closed from a crank arm 85 on the underside of the instrument projecting forwardly from the stub-shaft 80.

86 (Fig. 3) is a speed indicator of any 90 usual or preferred construction operatively connected by means 87 with the motor.

Referring again to the dynamics pointer and dial devices of Fig. 9, means is provided to frictionally hold them in any given position of adjustment, comprising a fixed plate 88 on the bottom board 11 of the instrument having a hole through which the stub-shaft 58 projects,—comprising further a bowed spring 89 on the same shaft with its ends 100 adapted to be pressed down into sufficient frictional contact with said plate by the adjustment of a collar 90 on said shaft to prevent the parts from moving out of their intended adjusted position, which otherwise 105 they would do on account of the constant pull of the heretofore described spring 50 (Fig. 5).

Referring now to the horn—in the first place, not only the neck but the entire horn 110 is insulated from the casing of the instrument because, in addition to the neck, the horn only touches the casing at its delivery end, and then only indirectly through the intervening surrounding strip of felt or 115 other suitable sound-deadening or packing material 91 (Fig. 12). 92 is a finishing bead of wood secured to the casing adjacent the mouth of the horn for appearance sake.

100, 100 are strips of felt across the top of 120 the interior of the instrument, upon which rests the cover 31 to prevent the latter from rattling.

What I claim is:

1. In a talking machine having a frame 125 and casing, an inclosed horn insulated in its entirety from said frame and casing so as not to receive extraneous vibrations; and a tone-arm mounted directly upon the neck of the horn and solely supported by the same, 130

whereby said tone-arm is insulated in its entirety by said horn from said frame and casing.

2. In a talking machine, a horn inclosed within the casing of the machine and secured thereto by intermediate insulation which insulates the entire horn from said casing, said horn having an upturned end; a shelf inclosed within the casing having a hole through which said horn end projects, the periphery of said hole being entirely free of contact with said horn end; and a tone-arm mounted above said shelf directly upon the said horn end and solely supported by the same, whereby said tone-arm is insulated in its entirety by said horn from said shelf and casing.
3. In a phonograph, the combination of a casing comprising a record-playing compartment; a closure therefor for the introduction of records into playing position and their removal; sound-reproducing mechanism, including a diaphragm, disposed within said compartment; a sound-conduit leading from said compartment; and packing means so arranged as to form a sound-tight joint between said compartment and its closure when the latter is closed, thereby to

prevent the escape from said compartment of sounds propagated from the exterior of 30 the diaphragm.

4. In a talking machine, a playing control-device, a flexible wire control for operating the same from a distance, motor-brake means, and a separate wire in said 35 flexible control operatively connected with the motor-brake means.

5. In a talking machine, a playing control-device, a flexible wire control for operating it from a distance comprising a relatively 40 45 slideable wire and a surrounding casing therefor, and further comprising a handle comprising two relatively slideable parts attached respectively to said wire and casing parts, motor-brake means, a third movable part on said handle, and another wire in the aforesaid casing whose one end is connected with said third movable part, and whose other end is operatively connected with said 50 brake means.

Signed at New York, N. Y., this 30th day of March, 1914.

JOSEPH H. DICKINSON.
